(57) **CLAIM**

The ornamental design for a cover for a cleaning implement, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a front side perspective view of a cover for a cleaning implement showing a first embodiment of our new design;

FIG. 2 is a rear view thereof;

FIG. 3 is a side perspective view thereof;

FIG. 4 is a top view thereof;

FIG. 5 is a bottom view thereof;

FIG. 6 is a close-up side perspective view of loop thereof;

FIG. 7 is a front side perspective view of a cover for a cleaning implement showing a second embodiment of our new design;

FIG. 8 is a rear view thereof;

FIG. 9 is a side perspective view thereof;

FIG. 10 is a top view thereof;

FIG. 11 is a bottom view thereof; and,

FIG. 12 is a close-up side perspective view of loop thereof.
